UNITED STATES PATENT OFFICE.

MORITZ SCHULZE, OF NEWARK, NEW JERSEY.

LADDER.

1,330,956.

Specification of Letters Patent. Patented Feb. 17, 1920.

Application filed February 25, 1919. Serial No. 279,138.

To all whom it may concern:

Be it known that I, MORITZ SCHULZE, a citizen of the Republic of Brazil, residing at Newark, in the county of Essex and State of New Jersey, have invented certain new and useful Improvements in Ladders; and I do hereby declare the following to be a full, clear, and exact description of the invention, such as will enable others skilled in the art 5 to which it appertains to make and use the same, reference being had to the accompanying drawings, and to characters of reference marked thereon, which form a part of this specification.

15 This invention relates, generally, to improvements in ladders; and, the present invention has reference, more particularly, to a novel extension means for the side-bars or members of ladders, which is adapted to be attached to and to be used with the supporting ends of the side-bars or members of the ladder, such means being adjustable, so that either or both of said side-bars or members can be made longer and extended, and that 25 the ladder can be properly placed against a building or the like, though the ground or surface upon which the ladder may be placed is uneven.

The present invention, therefore, has for 30 its principal object to provide the side-bars or members of a ladder with lengthening and adjusting devices for the proper support of the ladder upon uneven ground or surface, and to dispense with the dangerous 35 custom of placing unstaple props under the ends of the side-bars of the ladder, as is now ordinarily the custom.

Other objects of the present invention not at this time more particularly enumerated 40 will be clearly understood from the following detailed description of the present invention.

With the various objects of the present invention in view the said invention consists, 45 primarily, in the novel lengthening and adjusting means for the side-bars or members of ladders hereinafter more fully set forth; and, the present invention consists, furthermore, in the novel arrangements and combinations of the various devices and parts, as 50 well as in the details of the construction of said parts, all of which will be more fully described in the following specification, and then finally embodied in the clauses of the 55 claim which are appended to and which form an essential part of the said specification.

The invention is illustrated in the accompanying drawings, in which:—

Figure 1 is a front elevation of the lower portion of a ladder, the side-bars or members of which are shown with lengthening and adjusting means, illustrating one embodiment of the principles of the present invention; and Fig. 2 is a side elevation of the same.

Fig. 3 is a longitudinal vertical section, said section being taken on line 3—3 in said Fig. 2; Fig. 4 is a horizontal section of one of the side-bars or members of the ladder and the lengthening and adjusting means 60 connected therewith, said section being taken on line 4—4 in said Fig. 2; and Fig. 5 is a similar section of the same, said section being taken on line 5—5 in said Fig. 2.

Similar characters of reference are employed in all of the said above described views, to indicate corresponding parts.

Referring now to the said drawings, the reference-character 1 indicates the usual side-bars or members of a ladder, said bars 70 or members being connected by the usual rounds 2.

Each side-bar or member 1 is provided with a laterally extending hole or perforation 3, and with a recessed portion, as 4, in 85 which is fitted a plate 5, preferably secured in place by means of screws 6, or other suitable means of fastening, and each plate being provided with an outwardly extending holding or retaining means, in the form of a 90 lug, projection or rib 7, or the like. Each main member of the lengthening or adjusting means is in the form of a channeled member or element, comprising a face-portion 8 and two marginal side-members 9, all 95 adapted to embrace and to be slidably disposed upon the lower end-portions of the said side-bars or members 1, as illustrated in the several figures of the drawings. The lower portions of the face-portion 8 and the two side-members 9 may be connected by a web or connecting element 10, providing a foot and a means of protection for the end of each side-bar or member 1 of the ladder, as will be understood.

Each face-portion or member 8 is also provided in the proper place with an elongated opening or slot 11, and in their inner surfaces, the said face-portions or members 8 are formed with a plurality of receiving 100 depressions 12, or the like into any one of which the said lug, projection or rib 7 can

be brought into holding or retaining engagement, in the manner illustrated more particularly in Fig. 3 of the drawings.

To secure the said lengthening and adjusting devices in their movable embracing relations to the lower portions of the side-bars or members 1 of the ladder, bolts 13 are inserted in the holes or perforations 3, the shanks of said bolts passing into and through the elongated openings or slots 11 in said face-portions or members 8, with the screw-threaded portions 14 of said shanks projecting beyond said face-portions or members 8 and having suitably mounted thereon washers 15 and tightening or binding nuts 16.

The manner of assembling the various devices and parts and the adjustability of the lengthening and adjusting means with relation to the side-bars or members 1 of the ladder will be clearly understood from an inspection of the several figures of the drawings, and any further description of the same is therefore deemed unnecessary.

25 I claim:—

1. In a ladder, in combination with the supporting end-portions of the side-bars of the ladder, each side-bar being provided in its supporting end-portion with a hole, and a recessed portion extending laterally across the outer face-portion of each side-bar, adjusting means for lengthening said side-bars, each adjusting means comprising a plate inserted in a recessed portion and fixed therein, each plate being provided with an outwardly projecting retaining rib projecting beyond the outer face-portion of the side-bar, and a channeled member comprising a face-plate and two marginal side-members adapted to embrace and to be slidably disposed upon the said end-portions of the side-bars, each face-plate being formed with an elongated opening, a bolt in the hole of each side-bar, said bolts extending into and through said elongated openings and provided with tightening nuts, the face-plates of the channeled members being fur-

ther provided upon their inner faces with a plurality of laterally extending receiving depressions into any one of which a projecting rib aforesaid is adapted to be brought into retaining registration.

2. In a ladder, in combination with the end-portions of the side-bars of the ladder, each side-bar being provided in its supporting end-portion with a hole, and a recessed portion extending laterally across the outer face-portion of each side-bar, adjusting means for lengthening said side-bars, each adjusting means comprising a plate inserted in a recessed portion and fixed therein, each plate being provided with an outwardly projecting retaining rib projecting beyond the outer face-portion of the side-bar, and a channeled member comprising a face-plate 65 and two marginal side-members adapted to embrace and to be slidably disposed upon the said lower end portions of the side-bars, each face-plate being formed with an elongated opening, a bolt in the hole of each 70 side-bar, said bolts extending into and through said elongated openings and provided with tightening nuts, the face-plates of the channeled members being further provided upon their inner faces with a plurality of laterally extending receiving depressions into any one of which a projecting rib aforesaid is adapted to be brought into retaining registration, and a connecting web 75 connecting the lower supporting end-portions of the face-plate and marginal side-members of each channeled member, said webs extending beneath the free ends of the side-bars of the ladder, so as to reinforce and protect said ends of the side-bars.

In testimony that I claim the invention set forth above I have hereunto set my hand this 20th day of February, 1919.

MORITZ SCHULZE.
